HUB CAP

John J. Palotsee, 330 E. Front St., Youngstown, Ohio

Filed Sept. 28, 1960, Ser. No. 62,295

Term of patent 3½ years

(Cl. D14—30)

I claim:

The ornamental design for a hub cap, as shown.
